UNITED STATES PATENT OFFICE.

PAUL G. BACHMANN AND ARTHUR F. HENKE, OF CHICAGO, ILLINOIS.

METALLIC LACE.

1,075,320.

Specification of Letters Patent. Patented Oct. 14, 1913.

Application filed January 27, 1913. Serial No. 744,313.

To all whom it may concern:

Be it known that we, PAUL G. BACHMANN and ARTHUR F. HENKE, citizens of the United States, and residents of the city of 5 Chicago, in the county of Cook and State of Illinois, have invented certain new and useful Improvements in Metallic Laces; and we do hereby declare that the following is a full, clear, and exact description of the 10 same, reference being had to the accompanying drawings, and to the numbers of reference marked thereon, which form a part of this specification.

This invention relates to fastening or 15 lacing devices adapted to be used to fasten the overlapping edges of shoes, leggings, gloves, and the like.

It is an object of this invention to provide a neat, simple and effective lace or fastening 20 device for the overlapping or meeting edges of a shoe, and which, when in use, will connect the end of the underlying flap to the adjacent edge of the overlying flap, and thus hold the overlapping parts yieldingly 25 around the upper part of the foot and ankle.

It is also an object of the invention to provide a fastening device which will afford a yielding connection between the meeting edges of a shoe, or other similar wearing 30 apparel.

It is a further object of the invention to provide a lace which will not be likely to break or require renewal during the life of the article upon which it is secured.

35 It is finally an important object of this invention to provide a cheap, simple and durable metallic fastening device or lace which may be readily adjusted to suit the comfort of the user, and which will remain 40 in adjusted position without further attention during the life of the article to which it is attached.

The invention (in a preferred form) consists in the matters hereinafter described, 45 and more fully pointed out and defined in the appended claims.

In the drawings: Figure 1 illustrates a device embodying the invention applied to a shoe. Fig. 2 is an enlarged, fragmentary 50 view illustrating the manner in which a device embodying the invention is connected to the meeting edges of a garment. Fig. 3 is a fragmentary view of a strip having clasps embodying a part of the invention,

secured thereto. Fig. 4 is a fragmentary 55 view of a strip having hooks embodying a part of the invention, secured thereto. Fig. 5 is a section taken on line 5—5 of Fig. 2. Fig. 6 is a side elevation of one of the hooks shown in Fig. 4. Fig. 7 is a section taken 60 on line 7—7 of Fig. 8. Fig. 8 is a section taken on line 8—8 of Fig. 3, with the strip omitted. Fig. 9 is an end elevation of the clasp shown in Fig. 8. Fig. 10 is a section taken on line 10—10 of Fig. 5. Fig. 11 illustrates an instrument for use in connection 65 with the device embodying the invention.

As shown in the drawings: a device embodying the invention is illustrated for convenience, as applied to a shoe 1, the upper 2, 70 of which is provided with the usual slit 3, to facilitate admission of the foot within the same.

As shown in the various figures, 4, indicates a clasp, 5, a resilient lace, 6, a hook, 75 and 7 a button or grip adapted to be grasped by the user in fastening the member 5, to the hook. The clasp 4, comprises a top plate 8, which is bent and stamped to afford a slotted end wall 9, and a resilient base plate 10, 80 which is approximately parallel with, and spaced a short distance from said top plate. As shown in Figs. 7 to 9 inclusive, the top plate 8, is struck downwardly to afford a hook 11, and parallel guide flanges 12, on 85 each side of said hook 11. As shown, a relatively strong wire is coiled and flattened to afford a relatively long resilient member 5, adapted to extend through the slot 13, under the clasp, and there be adjustably engaged by means of the hook 11, which extends downwardly and engages one of the coils or loops of the same. A plurality of the clasps 4, and hooks 6, are secured in 90 spaced relation upon the strips of fabric 14 and 15, respectively in any suitable or convenient manner, and the strips are secured between the lining and the leather of the shoe on each side of the opening or slit 3, in such a manner that the outwardly directed 95 ends of the clasps and hooks project toward one another. The resilient members 5, are then pushed through the slot 13, and engaged by the hooks 11, in such a manner that they will be retained in position until 100 adjustment is deemed desirable. The button 7, is provided with a base 15, which is flanged downwardly and bent around the

105

end loop or coil of said member 5, to afford a firm attachment.

The operation is as follows: After the device has been assembled as has been previously described, it often happens that an adjustment of the laces must be effected to insure the user's comfort. If it is desired to tighten the shoe about the foot, the resilient members 5, are adjusted inwardly to the desired position and retained in adjusted position by the hooks 11, which act normally to prevent the withdrawal of the same from the clasp. In the event that the shoe fits too tightly about the foot, the free ends of the members 5, are slightly lengthened. This is accomplished by disengaging the hook from the lace by means of the instrument shown in Fig. 11, or any other suitable device which is provided with a flat plate 17, adapted to be inserted through the slot 13, and between the hook 11, and the member 5, to force the same apart. After the device has been suitably adjusted and it is desired to lace the shoe upon the foot, the button 7, is engaged by the fingers (or a button-hook, if preferred) and the free end of the coil or member 5, is engaged upon the hook 6, in such a manner that the shoe will at all times set snugly to the foot and ankle.

Of course, it is obvious that while we have described this invention as applied to a shoe, the device may be readily applied to many other articles. We have shown but a preferred form of the invention, and therefore

do not purpose limiting the patent granted 3 otherwise than necessitated by the prior art.

We claim as our invention:

1. A device of the class described comprising a clasp member embracing a top plate stamped to afford a slotted end wall, 41 and a base plate which is approximately parallel with, and spaced a short distance from said top plate, a downwardly directed hook integral with said top plate, a guide flange on each side of said downwardly directed hook, and a relatively long metallic member coiled and flattened to afford a strong resilient lace extending through the slot in said clasp member and normally engaged by said downwardly directed hook. 50

2. In a device of the class described a clasp member embracing a top plate, a resilient base plate connected therewith by means of an integral slotted wall, a hook integral with one of said plates, guide flanges on each side thereof, and a resilient member extending through the slot and engaged between said guide flanges by said hook and adapted for free adjustment inwardly but normally held from outward adjustment by said hook. 60

In testimony whereof we have hereunto subscribed our names in the presence of two subscribing witnesses.

PAUL G. BACHMANN.
ARTHUR F. HENKE.
